UNITED STATES PATENT OFFICE

132,291

DESIGN FOR AN ULTRA-VIOLET APPLICATOR

Norman A. Whittaker, Seattle, Wash., assignor of
one-fourth to L. Kristofferson, Seattle, Wash.

Application April 5, 1941, Serial No. 100,168

Term of patent 3½ years

To all whom it may concern:

Be it known that I, Norman A. Whittaker, a citizen of the United States, residing at Seattle, in the county of King and State of Washington, have invented a new, original, and ornamental Design for Ultra-Violet Applicators, of which the following is a specification, reference being had to the accompanying drawing, forming a part thereof.

In the drawing:

Fig. 1 is a view in front elevation of an ultra-violet applicator embodying my new design;

Fig. 2 is a view in side elevation thereof, with the applicator tube and its cord, together with the plug and its cord, omitted for convenience of illustration; and

Fig. 3 is a top plan view of Fig. 2.

I claim:

The ornamental design for an ultra-violet applicator, as shown.

NORMAN A. WHITTAKER.
